UNITED STATES PATENT OFFICE.

ADELARD BOUCHER, OF WINCHENDON, MASSACHUSETTS, ASSIGNOR OF ONE-HALF TO
ALFRED G. PELLETIER, OF WINCHENDON, MASSACHUSETTS.

ICE-CREAM FREEZER.

Application filed January 19, 1925. Serial No. 3,246.

To all whom it may concern:

Be it known that I, ADELARD BOUCHER, a citizen of Canada, residing at Winchendon, in the county of Worcester and State of Massachusetts, have invented certain new and useful Improvements in Ice-Cream Freezers, of which the following is a specification.

This invention relates to ice cream freezers, the invention having for an object to provide an improved and novel beater or agitator for the cream, having means applied thereto whereby a compound beating action can be given the beater, which is preferably made up of a number of relatively movable elements.

For further comprehension of the invention, and of the objects and advantages thereof, reference will be had to the following description and accompanying drawing, and to the appended claims in which the various novel features of the invention are more particularly set forth.

Fig. 1 of the drawing is an axial sectional view of an ice cream freezer having the invention applied thereto.

Fig. 2 is a fragmentary axial sectional view at right angles to Fig. 1.

Referring now to the drawing, the reference numeral 10 indicates the outer receptacle of the freezer, and 11 the inner receptacle, the latter being of cylindrical shape, the freezer being provided with a cover 12. This cover is formed with an aperture to receive the upwardly projecting stem or trunnion 14 of the beater. This beater comprises a vertical bar 15 that extends axially through the receptacle and is formed with a longitudinal slot 16 passing from side to side thereof and extending substantially the full length thereof. In this bar are mounted a series of beater elements comprising a ring 18 that is positioned substantially midway between top and bottom ends of the bar, and a pair of semi-rings 19 and 19' that are positioned one above and one below the central ring 18. These beater elements are arranged to have a slight rocking movement imparted thereto, being rotatably supported by pins 22 passing through the diametric elements 19^b of the semi-rings, and a cross-piece 18^b on the ring 18, the ends of these pins being fixed in the said bar 15. These members 18, 19, 19' are connected to one another to be rocked in unison by suitable

means such as the teeth 24 on the ring 18 engaging in notches 25 in the semi-rings.

The top trunnion 14 of the beater bar 15 extends upward through and is supported by, a frame element 28 to the underside of which the cover 12 is fixed, while the lower trunnion 14' of the beater bar is engaged freely in a suitable socket 29 in the bottom of the receptacle 11. Upon the end of the top trunnion 14 is fixed a bevel gear 30 that is engaged by a bevel pinion 31 on the inner end of a radially-extending horizontal shaft 32 supported by projections 28' from the frame 28, the shaft 32 having a crank handle 33 on its outer end for turning purposes.

To impart a rocking movement to the various elements of the beater I provide a vertical plunger pin 36 that is slidably mounted in the frame element 28 and is adapted to be engaged and pressed downwardly by means of two cams 37 on the underside of the gear 30. The two cams are diametrically opposed to one another, being positioned in vertical alignment with the crosspiece 19^b of the top beater element 19. The pin 36 is urged upwardly by the coiled expansion spring 39 surrounding the pin in a socket 40 in the frame element 28 and bearing upward on a collar 41 fixed to the pin, upward movement of the latter being limited by the collar 41 engaging a plug 42 fixed in the frame element 14.

In the operation of my improved device, the cream is placed as usual in the central receptacle 11, and the outer one is filled with the usual salt and ice mixture. When the handle 33 is turned, the beater is rotated, and as the top element 19 thereon comes under the pin 36 the latter comes under one of the cams 37 on the gear 30 and is depressed, imparting a slight rocking movement to all the beaters. When the beater element completes another half revolution the pin 36 is again depressed and the beaters rocked in an opposite direction.

Having thus described my invention, what I claim as new and desire to protect by Letters Patent of the United States is as follows:

1. In an ice cream freezer, a rotary beater, a frame element supporting said beater, said beater comprising a longitudinally slotted vertical shaft, a series of skeleton beater elements supported in said slot and consisting of a central ring and a pair of semi-rings lo

cated one above and the other below the central ring, means for rotating said shaft including a gear fixed to the upper end thereof, a pair of cams on the underside of said gear, and a plunger pin mounted in the said frame element and adapted to be engaged by said cams to engage in turn the top beater element to oscillate the latter.

2. In an ice cream freezer, a rotary beater, a frame element supporting said beater, said beater comprising a longitudinally slotted vertical shaft, a series of skeleton beater elements supported in said slot and consisting of a central ring and a pair of semi-rings located one above and the other below the central ring, means for rotating said shaft including a gear fixed to the upper end thereof, a pair of cams on the underside of said gear, and a plunger pin mounted in the said frame element and adapted to be engaged by said cams to engage in turn the top beater element to os-

cillate the latter, and means effecting operative connections between the various beater elements whereby the latter are caused to 25 oscillate in unison.

3. In an ice cream freezer, a rotary beater element comprising a slotted bar, and a series of beaters supported in the slot in the said bar and consisting of a centrally positioned ring and semi-rings on upper and lower sides thereof.

4. In an ice cream freezer, a rotary beater element comprising a slotted bar, and a series of beaters supported in the slot in the said bar and consisting of a centrally positioned ring and semi-rings on upper and lower sides thereof, means for rotating said bar, and means for oscillating the said beaters.

In testimony whereof I have affixed my signature.

ADELARD BOUCHER.
